ANTIRATTLER

Filed Nov. 8, 1926

UNITED STATES PATENT OFFICE.

PATRICK J. FITZGERALD, OF TORRINGTON, CONNECTICUT, ASSIGNOR TO THE FITZGERALD MANUFACTURING COMPANY, OF TORRINGTON, CONNECTICUT, A CORPORATION OF CONNECTICUT.

ANTIRATTLER.

Application filed November 8, 1926. Serial No. 147,033.

This invention relates to anti-rattling devices for doors and window panes, and more particularly to detachable devices of this type for use upon automobiles.

5 It is well known that in automobiles glass panes are employed, particularly with the so-called "closed" type of bodies, to slide into and out of pockets in the car frame or in a door frame, and when out of the frame 10 are guided along grooves which are lined with felt or similar material both to prevent rattling and to prevent the entry of dust and dirt when the pane is in the closed or raised position. It has been found, however, even with the use of such felt strips, 15 that the pane will vibrate and rattle within its frame.

The present invention provides a means of eliminating this rattle, and consists primarily in a friction member which forces the pane into tight contact with the felt at one side of each of the guide grooves. A spring is employed to maintain the member in such frictional and forcing relation 25 with the pane, and clamps are provided whereby the device may be quickly positioned and removed; and whereby the distance of the axis of the roller from the clamp, i. e., from the walls of the pocket, 30 may be immediately and accurately adjusted.

The device is composed of very few parts, is neat in appearance, has its operative elements substantially protected from the weather, and is of very slight incumbrance 35 upon the vehicle. Owing to its construction, it is adjustable so that in being positioned, it is brought automatically to fit a great variety of window and door frames.

With these and other purposes in view as 40 will appear in the course of the following specification taken in conjunction with the accompanying drawings, there are shown on the drawings:

Figure 1, a perspective view of the device 45 as applied to a door frame;

Fig. 2 is a longitudinal cross-section through the device of Fig. 1.

Fig. 2^a is a section on line 2^a—2^a of Fig. 2.

Fig. 3 is a side elevation partly in section 50 of a modified form of the device.

Fig. 3^a is an end view of the upper part of the device of Fig. 3.

In Fig. 1, the body 10 of the vehicle is conventionally represented as having a door 55 hinged thereto in any suitable manner not

shown. This door has a lower pocket with the upstanding posts 11, 12 thereon, respectively, at the outer and inner sides of the door. The door pocket with its walls 13 and 14 at the outside and inside defines the 60 opening 15 in which the glass pane P slides. The posts 11, 12 define a groove 18 which has the felt packing 17, 18 at the two sides thereof, in packing relation to the glass pane P. 65

The anti-rattling device of the present invention comprises a clamp member 20 which has its downwardly extending finger 20^a engaged against the inner face of the inner wall 14 of the pocket, and an outer clamping member 21 having a downwardly extending finger 21^a which engages over the customary bead or roll 22 adjacent the upper edge of the wall 14. These two fingers 20, 21^a therefore cooperate to hold the device it- 70 self in a detachable but rigid position opposite the center of the glass pane P. The two clamping members 20, 21 are mounted on a threaded sleeve 23: The member 20 has a threaded portion 24 to engage this sleeve, 80 while the member 21 has an aperture 25 for the loose reception of the sleeve 23. It will be understood that as the sleeve 23 is rotated within the portion 24, the position of the pivot pin 26, hereinafter more clearly de- 85 scribed, will be varied with relation to the clamping fingers 20^a, 21^a, and therefore with relation to the distance of its axis from the walls 13, 14 of the pocket. A lock nut 27 is likewise engaged upon the threaded sleeve 90 23 to jam the portion 24 and hold it in a predetermined and definite relation to the sleeve 23. A clamping nut 28 is likewise provided to force the loose clamping mem- 95 ber 21 into engagement with the outer face 20^a, 21^a of the door wall 14, whereby the door wall is tightly clamped between the fingers 20^a, 21^a.

The end of the threaded sleeve 23 away 100 from the glass pane has an inwardly extending flange 29 providing an aperture coaxial with the sleeve itself. A plunger 30 has a threaded end passing through this aperture and cooperating with a nut 31 on the exterior of the sleeve to form a stop to regulate 105 the amount of movement of the plunger 30 toward the glass pane. At the other end the plunger 30 has a collar 32 and extends as bifurcated parallel members 33 which support the pivot pin 26 of the friction roller 110

34. This friction roller is preferably made of fiber or similar material to prevent scratching the glass pane. The forwardly extended walls of the sleeve 23 are similarly cut out by a gash for the reception of the roller 34, and furnish a positive guide to prevent the rotation of the plunger 30 within the hollow sleeve 23, as shown in Fig. 2^a.

In operation, the clamping finger 20^a is slipped into position with the lock nut 27, the other clamp 21 and the clamping nut 28 loosened or removed. The sleeve 23 is then rotated until the friction roller 34 is in a suitable frictional contact with the glass pane 16, and the pivot pin 26 thereof is in position at right angles to the line of movement of the pane P. For this, the friction roller 34 should be engaged forcibly with the pane so that it exerts a thrust along the plunger 30 toward the right in Fig. 2, with a resultant compression of the spring 35 which is compressed between the collar 32 and the flange 29 of the sleeve. If desired, the nut 31 may be turned up to regulate the initial tension upon the spring 35.

The lock nut 27 is now screwed tightly against the portion 24 of the clamp 20 to retain the latter rigidly with regard to the sleeve 23. The second clamp 21 is now brought tightly into position on its respective side of the wall 14, and the clamping nut 28 screwed home so as to hold the clamp 20, 21 tightly and rigidly applied to the upper edge of the door pocket wall 14.

35. As the pane is raised or lowered, the friction roller 34 forces it outward against the felt 17 at the side shown. It will be understood that a similar felted groove is provided at the outer edge of the pane P in the customary manner, and that it is similarly brought into play. If the pane P does not move truly in its guides, the roller 34 will give and take under the action of its spring 35 so that at all times an outward position is given to the pane P, whereby rattles and other effects of free vibration are eliminated from this part of the vehicle.

The device may be quickly and easily removed by reverse operation, by loosening the nut 28, so that the clamp 21 is liberated, whereupon the device may be rocked out of position.

When the pane P has retreated completely within the pocket 15, the roller 34 is of course disengaged but is prevented from flying out of the assemblage along with the plunger 30 by reason of the stop nut 31 on the plunger.

In the modified form of Fig. 3, most of the elements are as already described, but the lock nut 31 on the end of the plunger 30 has been replaced by a cotter pin 40 which is passed through the diametrical slot in the adjacent end of the threaded sleeve 23, and thus serves to maintain the plunger 30

against rotation within the sleeve 23. In this form of execution, the sleeve terminates short of the roller 36, and only the bifurcated ends 33 of the plunger 30 project toward the glass pane. ⁷⁰

The method of employing this device is the same as that of the form of Fig. 2.

It is obvious that the invention is not limited to the specific modifications shown, but that it may be modified in any wise within ⁷⁵ the scope of the appended claims.

What is claimed as new is:

1. In a quick-detachable anti-rattler for sliding panes movable into and out of a pocket casing, a friction member to engage the pane, means to resiliently force said member and therewith the pane toward one wall of said pocket, clamping devices to detachably engage the faces of the other wall of the pocket to support said member and means, and adjustment means to permit regulation of the distance from said clamping devices to the contact portion of said friction member.

2. In a quick-detachable anti-rattler for ⁹⁰ sliding panes movable into and out of a pocket casing, a friction member to engage the pane, means to resiliently force said member and therewith the pane toward one wall of said pocket, clamping devices to detachably engage the faces of the other wall ⁹⁵ of the pocket to support said member and means, adjustment means to permit regulation of the distance from said clamping devices to the contact portion of said friction member, and a stop on said member to limit the movement thereof in the direction of the pane.

3. In a quick-detachable anti-rattler for ¹⁰⁵ sliding panes movable along guides into and out of a pocket casing, clamp fingers to engage the faces of one wall of said casing, a hollow sleeve to which said fingers are secured at adjusted positions along its length, a friction roller to make contact with the ¹¹⁰ pane and push it against the opposite walls of its guides, and means carried by said sleeve to support said roller and hold it resiliently against said pane.

4. In a quick-detachable anti-rattler for ¹¹⁵ the sliding door and window panes of automobiles and the like, an externally threaded sleeve having an internal flange at one end, a first internally threaded member adapted to engage said sleeve and having a clamp ¹²⁰ finger adapted to engage in the pane opening of the door or window casing, a lock nut engaged with said sleeve to lock said member in position thereon, a second member having an aperture to fit said sleeve and adapted to engage an outer face of the door or window casing, a clamp nut on said sleeve to draw said clamps together whereby to tightly engage said casing, a plunger in said sleeve having a collar thereon and extended ¹²⁵ ¹³⁰

at the opposite end into the casing a pivot pin in such extension at right angles to the axis of the sleeve, a friction roller on said pivot pin, a spring in said sleeve in compression between said collar and the internal flange of said sleeve, said plunger at its end away from said roller extending past said internal flange to the exterior of said sleeve, and a stop member on said plunger external to said sleeve and cooperating therewith whereby to limit the movement of said plunger under the impulsion of said spring.

5. In an anti-rattler for a sliding pane, a sleeve, means to hold said sleeve at substantially a right angle to said pane at an adjusted distance therefrom, a member slid able in said sleeve toward and from the pane, a spring acting between said sleeve and member to force the latter toward the pane, a 10 friction roller journalled at the pane end of said member; said roller being movable in a slot in said sleeve whereby to prevent movement of said roller about the axis of said member.

15 6. In an anti-rattler for a sliding pane, a sleeve, means to hold said sleeve at substantially a right angle to said pane at an adjusted distance therefrom, a member slid 20 able in said sleeve toward and from the pane,

a spring acting between said sleeve and member to force the latter toward the pane, a friction roller journalled at the pane end of said member, said sleeve having a diametral gash in its end to receive said roller whereby to prevent movement thereof about the 35 axis of said member.

7. In an anti-rattler for a sliding pane, a sleeve, means to hold said sleeve at substantially a right angle to said pane at an adjusted distance therefrom, a member slid able in said sleeve toward and from the pane, a spring acting between said sleeve and member to force the latter toward the pane, said sleeve having an internal flange, said member having a stem projecting through an 40 aperture of said flange, a friction roller journalled at the pane end of said member, said roller being movable in a slot in said sleeve whereby to prevent movement of said roller about the axis of said member and adjusting 45 means on the end of said stem projecting through said flange to limit and adjust the movement of said roller in the direction of said pane.

25 In testimony whereof, I affix my signature.

PATRICK J. FITZGERALD.
